UNITED STATES PATENT OFFICE.

MATTHEW C. SHARPNACK, OF OMAHA, NEBRASKA.

HYDRAULIC OIL-PUMPING MECHANISM.

1,322,358.

Specification of Letters Patent. Patented Nov. 18, 1919.

Application filed October 22, 1918. Serial No. 259,237.

To all whom it may concern:

Be it known that I, MATTHEW C. SHARPNACK, a citizen of the United States, residing at Omaha, in the county of Douglas and 5 State of Nebraska, have invented certain new and useful Improvements in Hydraulic Oil-Pumping Mechanism, of which the following is a specification.

This invention relates to hydraulic oil-pumping mechanism, and has for its object, broadly, to provide means for pumping oil, or a mixture of oil and sand from oil wells, the construction to be such that the parts may be conveniently manufactured and 10 assembled and will be convenient and durable in use. Other objects more specific will be explained hereinafter.

In the accompanying drawing which illustrates one embodiment of the invention, 20 Figure 1 is a view in side elevation of receiving tanks for use in connection with the pumps, certain conducting pipes, a main discharge pipe, and valves being shown in longitudinal section. Fig. 2 is a transverse section through the strainer on line 2—2 of Fig. 7. Fig. 3 is a side view of the strainer. Fig. 4 is a detail relating to Fig. 1 to show the preferred mounting for a movable delivery pipe. Fig. 5 is a plan view of the 25 tanks and their connections. Fig. 6 is a detail showing the preferred connection for the auxiliary conducting pipes with the main conducting pipe, a flexible section being shown partly broken away. Fig. 7 is a sectional detail to clearly show the connection of one of the auxiliary conducting pipes with the discharge pipe, and the arrangement of the strainer, a nozzle and a stirring receptacle. Fig. 8 is a sectional 30 view of the main discharge pipe looking toward its apertured flange.

Referring now to the drawing for a more particular description, numeral 1 indicates a casing of conventional type used in oil 45 wells, and which may have any required length, depending upon the depth of the well. I provide, within the casing, a main conducting pipe 2 having an apertured bottom plate 3, and secured to said bottom 30 50 55 plate 3 to project beyond the ends of the casing and main conducting pipe are a plurality of conducting tubes 4.

Numerals 5 indicates an apertured stirring receptacle which is mounted upon the outer ends of the tubes 4, and at 6 is indicated a cylindrical strainer interposed between the

receptacle 5 and bottom 3. At 7 is indicated an inwardly projecting nozzle, its divergent end being mounted in one of the apertures formed in the top of the receptacle 5. 60

The parts thus described may be secured in connected relation by any suitable means, but preferably the tubes 4 are threaded in the bottom plate 3, as best shown in Fig. 7, and by use of nuts 8 threaded on the lower 65 ends of the tubes 4, the cylindrical strainer may be firmly secured in the position above mentioned, and the receptacle 5 and nozzle 7 carried thereby will be secured to the bottom 3 of the main conducting pipe 2. Numeral 9 indicates a discharge pipe in communication with the nozzle 7 for use in elevating water, or oil and sand mixed with water.

Numerals 10 indicates a pump adapted to 75 be actuated by any suitable means for pumping water from the tank 11 and discharging it to the pipe 2, said pump 10 being provided with a supply pipe 12 communicating with tank 11 and having a pipe 13 in communication with said main conducting pipe 2, and it will be understood that when the pump 10 is actuated water will be delivered to the receptacle 5 from the pipe 13 and may pass upwardly through the pipe 9 to be 80 delivered to the tank 11.

Numerals 14, 15 and 16 indicate tanks, each being provided with a pipe 17 in communication with an endless line pipe 18, subject to a control of a valve 19, and at 85 90 95 20 are indicated a plurality of pumps adapted to be actuated by any suitable means for causing water to be conducted under pressure to the discharge pipe 9 from the pipe 18 through pipes 21, said pipes 21 having any required length and being disposed in the annular chamber 22, intermediate the walls of pipes 2 and 9.

The pipe 12 is provided with a valve 19', and while I have shown only one pump 10 100 for causing a discharge of water through the tubes 4, and through the receptacle 5 and the nozzle 7, it will be understood that the bore of the pipes may have any desired proportion, and the pressure of water in 105 the pipe 2 effected by the pump 10 may be adequate to cause the water to move with great force for entering the discharge pipe 9. Also the pipes 21 may have any required bore and may be of suitable lengths, and 110 the pressure of water in pipes 21 provided by the pumps 20 may be adequate to cause

water to move upward in the pipe 9 with great force, depending of course upon the lengths of pipes 21 and the depth of the well, the result in operation being that oil or sand or oil mixed with sand will enter the apertures *a* of the cylindrical strainer by operation of suction, and from thence will move upwardly within the pipe 9, and will be discharged, its delivery being to one of the tanks.

Numerals 23 indicates a delivery pipe adapted to be swung horizontally on its mounting upon the upper end of the pipe 9, for delivering the mixture of water, sand and oil to any one of the tanks 11, 14, 15 or 16, said pipe 9 being at equal radial distances from the tanks.

Water may be obtained from any suitable source for a movement through pipes 13 and 21 by operation of the pumps 10 and 20. Since, as shown in Fig. 1, the pipes 17 and 12 communicate approximately midway between the tops and bottoms of the tanks, water practically free from sand or oil, will be supplied to the pumps, the oil remaining in the upper part and the sand settling to the bottom of each tank. By use of any one of the valves 19 or 19', a tank may be segregated from the pipe 18 and the oil and other contents of a tank, thus disconnected, may be removed, and on this account, a plurality of tanks and the movable pipe 23 are desired.

Each pipe 21, at its lower end, is provided with a curved discharge nozzle *b*, as best shown in Fig. 7, which terminates approximately at the center of the bore of the pipe 9. Numerals 24 indicate a plurality of sleeves, the bore of each being formed outwardly divergent toward its ends, these being mounted in the pipe 9, and preferably threaded therein, with its lower end circumscribing a nozzle *b* of a pipe 21; and at 25 is indicated a sleeve similar in form to a sleeve 24, said sleeve 25 being threaded in the lower end of the pipe 9 to be disposed in an aperture of the plate 3 for maintaining said pipe 9 at the middle of the bore of the pipe 2. The sleeves provide for the pipe 9 a plurality of constricted passageways adjacent to the nozzles which aid materially in sustaining the weight of the column of water, sand and oil in said pipe while the pumps are operating.

The herein described mechanism is for use in instances where sand has been encountered in oil wells in such abundance that operation has not been practical, the sand being drawn toward and packed about the lower end of the pipe by suction, and operating as an obstruction to prevent pumping of oil. By use of the herein described mechanism any sand, which otherwise might operate as an obstruction, will be removed, and for that purpose the strainer, best shown in Figs. 2 and 3, consists of a hollow

cylinder provided with elongated intake apertures *a*, above mentioned, and having substantially parallel bearing-blocks *c* formed on its inner side, said bearing-blocks being provided with transversely curved 70 grooves *d* (Fig. 2.), their curvature corresponding to the shape of the tubes 4 for receiving said tubes, and thereby to prevent injury or wear of the latter which otherwise would be caused from contact with inwardly moving sand.

In order that water may be discharged below the receptacle 5 for removal of accumulated sand, the bottom of said receptacle is provided with apertures *e*, and by 80 use of the pump 10, the pumps 20 not being actuated, water may be discharged through said apertures for that purpose.

The lower end of pipe 9 is provided with an outwardly projecting circular flange 26 85 having apertures *f* formed therein corresponding in number to the number of tubes 4, and as best shown in Fig. 7, the flange 26 is disposed on the plate 3, with its apertures *f* disposed in register with the tubes 4. 90 However, in order that the water may be retained in the pipe 2 when the device is not in operation, and to prevent loss of time in refilling said pipe 2, the pipe 9 may have a limited revoluble movement to dispose the apertures *f* in non-register with the tubes 4, the pipes 21 moving with the pipe 9; and to permit this limited revoluble movement of the pipe 9 each pipe 21 is provided with a flexible section 27, as shown in Figs. 1, 5 100 and 6.

Fig. 6 illustrates a detail considered to be an advantage in construction, an apertured casting 27 being provided as a cap or head-piece for a mounting on the upper end of the main conducting pipe 2, suitable packing 28 and a packing-ring 29 being employed in connection with the outwardly projecting flange 30 of said pipe, and suitable packing-rings 31 being employed for compressing the packing 32 for a bearing upon pipes 9 and 21. Fig. 4 shows a collar 33 provided for the inner end of the delivery pipe 23, and by means of the ring 34, the packing 35 may be compressed, the pipe 9 being provided with 115 a terminal, outwardly projecting flange 36.

At 37 (Fig. 1.) is indicated an overflow pipe in communication with the pipe 13 found to be of advantage to facilitate actuation of the pump 10 in certain instances, as when the pipe 2 contains water and when first applying power for actuating said pump 10. By opening the valve 38, water will move in a direction of least resistance, this being through the pipe 37. As a feature of convenience in manufacture and for assembling the parts, sections 39 are provided for the pipe 9, and have a threaded connection therewith as best shown in Fig. 7, for a mounting of the nozzles *b*.

While I have described construction in detail, I do not wish to be understood as limiting myself in this respect, and changes may be made in size, form, proportion and minor details, since the scope of the invention is determined by the appended claims.

What I claim and desire to secure by Letters Patent is,—

1. In hydraulic oil-pumping mechanism, an upright conducting pipe having a closure-plate at one of its ends, a discharge pipe within the conducting pipe engaging the closure-plate, a strainer in communication with the discharge pipe, a stirring-receptacle in communication with the discharge pipe and conducting pipe, a pump for delivering a liquid under pressure to the conducting pipe for a movement to the stirring-receptacle and from the stirring-receptacle to the discharge pipe to cause suction from the strainer to said discharge pipe, and a plurality of pumps for delivering liquid under pressure to said discharge pipe.
2. In hydraulic oil-pumping mechanism, an upright conducting pipe provided at its lower end with a closure-plate, a discharge pipe within the conducting pipe upon the closure-plate, a stirring-receptacle communicating with the conducting pipe, an apertured sleeve between the stirring-receptacle and closure-plate, said stirring-receptacle being in communication with the discharge pipe to permit water under pressure within the conducting pipe to move therefrom through the stirring-receptacle for a movement to the discharge pipe to cause suction inwardly of the aperture of the sleeve.
3. In hydraulic oil-pumping mechanism, an upright conducting pipe provided at its lower end with a closure-plate, tubes communicating with the conducting pipe and projecting outwardly of the closure-plate, a stirring-receptacle communicating with said tubes, a sleeve having intake apertures formed in its wall and interposed between the receptacle and said closure-plate, a discharge pipe within the conducting pipe communicating with the stirring-receptacle, and intake apertures of the sleeve, and means to conduct a fluid under pressure to the conducting pipe for a movement of said fluid through the stirring-receptacle to the discharge pipe for causing suction inwardly of the apertures of said sleeve.
4. In hydraulic oil-pumping mechanism, an upright conducting pipe provided at its lower end with a closure-plate, a stirring-receptacle disposed outwardly of the lower end of the conducting pipe in communication therewith, a sleeve interposed between the re-
- ceptacle and closure-plate and having intake apertures, a discharge pipe having a constricted, terminal passageway communicating with the intake apertures of the sleeve and disposed within the conducting pipe, an upwardly convergent nozzle communicating with the constricted passageway and said receptacle, and a fluid under pressure in the conducting pipe for moving through the stirring-receptacle and nozzle and the constricted passageway of said discharge pipe for causing suction inwardly of the apertures of the sleeve.
5. In hydraulic oil-pumping mechanism, the combination of an upright conducting pipe provided at its lower end with a closure-plate a discharge pipe within the conducting pipe having a constricted passageway, a stirring-receptacle communicating with the conducting pipe, a sleeve between the receptacle and closure-plate and having intake apertures in communication with the constricted passageway, an upwardly convergent nozzle communicating with the receptacle and having its upper end circumscribed by the constricted passageway to permit a movement of water under pressure from the receptacle to the constricted passageway for causing suction inwardly of the apertures of the sleeve.
6. In hydraulic oil-pumping mechanism, a main, upright conducting pipe provided at its lower end with a closure plate, a discharge pipe within the conducting pipe upon the closure-plate and having constricted passageways at longitudinal intervals, a stirring-receptacle communicating with the main conducting pipe, an apertured sleeve between the stirring-receptacle and closure-plate, a nozzle circumscribed by a constricted passageway of the discharge pipe and in communication with the stirring-receptacle to permit water under pressure within the main conducting pipe to move therefrom through the stirring-receptacle and nozzle to said discharge pipe for causing suction inwardly of the apertures of the sleeve, and a plurality of auxiliary conducting pipes within the main conducting pipe, each having a nozzle circumscribed by a constricted passageway of the discharge pipe for conducting water under pressure to said discharge pipe.

In testimony whereof, I have affixed my signature in presence of two witnesses.

MATTHEW C. SHARPNACK.
